2,439,600

MANUFACTURE OF MOTOR FUEL BY ALKYRATION WITH A LIGHT CRACKED NAPHTHA

Arthur R. Goldsby, Beacon, and Louis A. Clarke, Fishkill, N. Y., assignors to The Texas Company, New York, N. Y., a corporation of Delaware

No Drawing. Application April 23, 1943,
Serial No. 484,214

11 Claims. (Cl. 260—683.4)

1

This invention relates to the manufacture of motor fuels and has to do particularly with a process for improving cracked naphthas by treating the naphtha in the presence of an alkylation catalyst and an isoparaffin, under such conditions that the isoparaffin is alkylated by the unsaturated constituents of the naphtha.

This is a continuation-in-part of our copending application, Serial No. 295,048, filed September 15, 1939, and now abandoned.

It has been proposed in U. S. Patent No. 2,260,944 to treat cracked naphthas or cracked gasolines under alkylation conditions with a low-boiling isoparaffin and strong sulfuric acid to obtain alkylation of the isoparaffin with the olefinic constituents of the oil. In the treatment of cracked gasoline and naphthas by this method, the life of the catalyst has been short, due in part to interaction between the catalyst and aromatic components of the oil. Also alkylated aromatics of higher boiling range than gasoline are formed whereby the yield of desired product is reduced. It has now been found that greatly improved results may be obtained by treating a cracked naphtha fraction or cut boiling below the boiling range of the major portion of the aromatic constituents under different and critical conditions of isoparaffin to naphtha ratio and catalyst to naphtha ratio as hereinafter described.

The cracked naphtha or fractions of cracked gasoline, which may be treated according to the invention, should preferably have an end boiling point not in excess of about 200° F. Suitable materials for treatment include fractions of thermally and catalytically cracked gasoline, although it has been found that the low-boiling fractions of gasoline resulting from the catalytic cracking of oils constitute a superior charge stock over similar fractions from a gasoline obtained by thermal cracking. Best results have been obtained by treating certain closely fractionated cuts, particularly a fraction comprised essentially of a mixture of C₅ and C₆ hydrocarbons. It is contemplated, however, that fractions consisting essentially of individual fractions such as C₅, C₆, and C₇ hydrocarbons or any mixture thereof may be used.

In accordance with the invention, the products of thermal or catalytic conversion of hydrocarbon oil are fractionated to separate a light cracked naphtha fraction, and the light naphtha fraction is treated with low-boiling isoparaffins, such as isobutane or isopentane, in an amount in excess of the olefin content and pref-

2

erably in an amount greater than the naphtha by volume, for example, about 2 or 3 or more times the volume of the naphtha, and in the presence of an alkylation catalyst under alkylation conditions. The catalyst may be a suitable alkylation catalyst such as aluminum chloride and anhydrous hydrogen chloride, boron trifluoride and water complex, and preferably strong sulfuric acid of about 90 to 100%, for example about 94 to 98% H₂SO₄. The conditions for alkylation involve temperatures of about 0 to 100° F., liquid phase, intimate contact between the hydrocarbons and catalyst, a volume ratio of catalyst to naphtha of about 1/2:1 to 2:1 or greater, and a time of contact of about 5 to 150 minutes.

In practicing the invention, there is prepared a naphtha fraction suitable for treatment which, for example, may be obtained from cracked naphtha conversion products by fractional distillation. The fraction, with or without additional treatment, such as caustic wash or desulfurization, is treated with an alkylation catalyst, such as 98% sulfuric acid in the presence of a large excess of low-boiling isoparaffins, such as isobutane. The naphtha is preferably introduced into a mixture containing the isoparaffin and the catalyst, under such conditions that the ratio of isoparaffin to olefins is fairly high at all times. The treated naphtha containing the alkylate is separated from the catalyst, caustic washed, and after fractionation and stabilization may be used for the manufacture of motor fuel.

According to one method of operation, cracked naphtha conversion products are separated by fractional distillation into a high-boiling naphtha fraction and a low-boiling naphtha fraction. It has been found that a low-boiling cut usually amounting to about 15 to 50% of an ordinary cracked gasoline, is substantially free from aromatics. The low-boiling fraction is then alkylated with the isoparaffin to produce a high yield of high anti-knock product suitable for the manufacture of motor fuel, and may advantageously be reblended with the high-boiling fraction.

The reactions are not fully understood and the invention is not predicated on any theory of reaction. There appears to be alkylation of the isoparaffin by the olefins in the cracked naphtha to form high anti-knock saturated branch chain hydrocarbons of the gasoline boiling point range. The reaction is also accompanied by a substantial reduction in sulfur content and improvement in color and gum stability of the treated product. Also, the lead susceptibility, that is,

the anti-knock response of the naphtha on addition of tetraethyl lead, is greatly improved.

In order to illustrate the advantages of the present invention, examples will now be given of the treatment of cracked naphthas with sulfuric acid, with and without the presence of added isobutane.

Example I

Hydrocarbon oil was thermally converted in a conventional manner in a Holmes-Manley cracking unit at cracking temperatures and pressures to reduce a substantial proportion thereof to hydrocarbon products within the gasoline boiling range. The conversion products were fractionated to separate a light C₅—C₇ cracked naphtha fraction having a boiling range of 95–196° F. and a heavier cracked naphtha fraction having a boiling range of 197–397° F. The said light fraction contained 41.8% by weight of olefins, and amounted to about 31% by volume of the total cracked naphtha boiling between 95° F. and 297° F. Portions of the said light fraction were then treated with strong sulfuric acid with and without the presence of added isobutane under the conditions and with the results as set forth in the following table:

	Untreated	Treated in the presence of added isobutane	Treated in the absence of added isobutane
Isobutane to naphtha, volume ratio		3:1	
Reaction time, minutes	150	120	
Temperature, °F	71	67	
Acid, per cent H ₂ SO ₄	97	97	
Ratio of acid to gasoline, volume ratio	0.67:1	0.75:1	
Yield of 400 end point gasoline-basis weight 200 end point charge, per cent	105	63.7	
Total yield butane-free liquid-basis 200 end point charge, per cent by weight	110	75.2	
Concentration of recovered acid, per cent H ₂ SO ₄	92.4		
<i>Tests on Gasoline</i>			
Color	+25	+30	+30
Sulfur, per cent	0.017	0.005	0.013
Bromine Number	83	0	1
Voorhees-Eisinger Induction Test	17+ hrs.	22+ hrs.	195 mins.
Octane Number, CFRM	75.2	75.2	60.5
Octane number, plus 1 cc. tetraethyl lead	78.3	86.9	71.4
Initial Boiling Point	95	110	99
End Point	196	356	392

From the above results, it will be observed that without the addition of isobutane only 63.7% of the charging material was recovered as gasoline, whereas with a 3:1 ratio of isobutane to gasoline the yield was 105%. Without any treatment, the untreated gasoline with 1 cc. of added tetraethyl lead per gallon is improved only from 75.2 to 78.3 octane number. Although the susceptibility to lead is improved by simple acid treatment, the base octane number was lower. Thus, the octane number was 60.5, and with 1 cc. tetraethyl lead per gallon, the octane number was 71.4. With a 3:1 isobutane-to-gasoline ratio, the octane number was 75.5 and the lead susceptibility is very good; thus, 1 cc. of tetraethyl lead per gallon gave an octane rating of 86.9. The acid treatment alone lowers the sulfur content from 0.017 in the charge gasoline to 0.013 in the treated product. With a 3:1 isobutane-to-gasoline ratio, however, the sulfur content was reduced to 0.005%. The induction test shows 195 minutes for the acid-treated charge in comparison with over 17 hours for the untreated charge stock, and

over 22 hours for the product treated with 3:1 isobutane-to-gasoline ratio.

Another portion of the same 95–196° F. cut of cracked gasoline was treated under essentially similar conditions as set forth above in the middle column of the table, except that a lower isobutane-to-naphtha ratio of about 1:1 was employed, as shown in the following table:

10	Isobutane/naphtha vol. ratio	1:1
15	Reaction time—min	240
20	Temperature, °F	68
25	Acid % H ₂ SO ₄	96.6
30	Acid/gasoline vol. ratio	0.67:1
35	Yield of 400 end point gasoline basis naphtha charged, % by wt	92.6
40	Octane number—CFRM	72.9
45	Bromine number	3

Comparing these results with the middle column of the first table, it will be seen that the lower isobutane-to-naphtha volume ratio of 1:1 gave a substantially reduced yield of 400° F. end point gasoline of lower octane and higher bromine number than when a substantial volume excess of isobutane to naphtha was employed.

Still another portion of the same 95–196° F. cut of cracked gasoline was treated under essentially similar conditions as set forth in the middle column of the first table, except that a lower volume ratio of acid to naphtha of 0.33:1 was employed, as shown in the following table:

35	Isobutane/naphtha vol. ratio	2:1
40	Reaction time—min	150
45	Temperature, °F	72
50	Acid % H ₂ SO ₄	97
55	Acid/gasoline vol. ratio	0.33:1
60	Total yield debutanized gasoline basis naphtha charged, % by wt	100
65	Concentration of recovered acid—% H ₂ SO ₄	87.7

Comparing these results with the middle column of the first table, it will be seen that the lower acid-to-gasoline volume ratio of 0.33:1 gave a substantially reduced yield, and a greater acid deterioration as shown by the acidity of the recovered acid, than when a volume ratio of acid to gasoline in excess of about 0.5:1, namely, about 0.67:1, was employed.

Example II

A C₅—C₆ cut of catalytically cracked gasoline containing 83.7% by weight of olefins and a heavier naphtha fraction were separated by fractionation from conversion constituents obtained by the catalytic cracking of gas oil in the presence of a silica-alumina type catalyst. This catalytic cracking was carried out in well-known manner by passing the gas oil to be converted through a cracking zone containing an active cracking catalyst and maintained at active cracking temperature, such as about 900–1000° F., keeping the oil in contact with said cracking catalyst within said cracking zone for a period sufficient to convert a substantial portion of said oil into motor fuel constituents. The fractionation of the cracked products described above separated a light naphtha fraction having a boiling range of 81–157° F. and which was substantially free of aromatic constituents and contained a substantial amount of olefinic constituents having a high acid heat. The said light naphtha fraction contained substantially equal proportions of C₅ and C₆ hydrocarbons. The said fraction so segregated was then passed in a mixture with isoparaffins in

such proportion that the molar ratio of isoparaffin to olefinic constituents was not less than 1:1 in contact with an active alkylating catalyst capable of accelerating the union between isoparaffins and olefins to form a saturated product, the said mixture being maintained in contact with said catalyst for a period sufficient to alkylate a substantial amount of the olefins in the light naphtha fraction and thereby increase the boiling range thereof. The saturation of the olefinic content of the fraction by this method of treatment gave a gasoline having a low acid heat as is evident from the low bromine number, and produced a product having a high octane number lead response as above described. The conditions of operation and the results obtained in this run are set forth in the following table:

Isobutane to naphtha wt. ratio	3:1
Reaction time—min.	90
Temperature, ° F.	73
Acid % H ₂ SO ₄	98
Acid/gasoline wt. ratio	3:1
Acid/gasoline vol. ratio	1.2:1 (approx.)

311° F. end point gasoline fraction

Wt. % yield basis of olefin charged	198.9
Bromine number	1.0
Octane number—CFRM	89.7

311-400° F. gasoline fraction

Wt. % yield basis of olefin charged	24.0
Bromine number	1.0

Residue

Wt. % yield basis of olefin charged	14.8
Recovered acid % H ₂ SO ₄	94.2

The above results show that the light catalytically-cracked naphtha fraction constitutes a superior charge stock over a similar fraction of thermally-cracked naphtha for purposes of the present invention. Alkylate formed from the light fraction may be combined with the heavy naphtha fraction separated in the fractionation of the products of the catalytic cracking treatment as above described, to thereby form a gasoline blend containing light naphtha alkylate and heavy catalytically-cracked naphtha.

Example III

A portion of the heavy fraction of catalytically-cracked naphtha from which the C₅-C₆ cut had been removed (Example II above), was further fractionated to separate a C₇ cut containing 73.6% by weight of olefins and having a boiling range of 158-207° F. This C₇ cut was then alkylated under the conditions and with the results set forth in the following table:

Isobutane/naphtha wt. ratio	3.3:1
Isobutane/olefin wt. ratio	4.5:1
Reaction time—min.	90
Temperature, ° F.	72
Acid % H ₂ SO ₄	98
Acid/naphtha wt. ratio	2.5:1
Acid/olefin wt. ratio	3.4:1
Acid/naphtha vol. ratio	1:1 (approx.)

86-210° F. debutanized alkylate fraction

Wt. % yield basis olefin charged	74.2
Octane number—CFRM	78.8

210-437° F. alkylate fraction

Wt. % yield basis of olefin charged	67.1

Residue

Wt. % yield basis of olefin charged	22.0

311° F. end point debutanized alkylate

Wt. % yield basis of olefin charged 101.5

The above results indicate that this fraction is not as good a charge stock as the C₅-C₆ fraction, and that the C₇ constituents are about the highest boiling cracked naphtha materials that can be alkylated in accordance with the present invention with the advantageous results and low catalyst consumption as above described.

The process of the present invention is an effective method of desulfurizing hydrocarbons and may advantageously be applied to the alkylation of a low-boiling fraction derived from a stock of high sulfur content.

As illustrated by the examples set forth above, the present invention enables cracked naphthas to be markedly improved in lead response and other properties, rendering them eminently suitable for high anti-knock motor fuels, such as base stock for the manufacture of aviation gasoline. As distinguished from conventional acid-treating, this is accomplished without loss in yield and, in most instances, with an appreciable increase in yield. Moreover, by the use of the operating conditions set forth above, including a substantial volume excess of isoparaffin or isobutane to naphtha, and a volume ratio of catalyst to naphtha of about 0.5:1 to 2:1 and higher, a substantially saturated product is obtained with marked reduction and economy in catalyst consumption.

Obviously many modifications and variations of the invention, as hereinbefore set forth, may be made without departing from the spirit and scope thereof, and therefore only such limitations should be imposed as are indicated in the appended claims.

We claim:

1. The method in the manufacture of motor fuel hydrocarbons, which comprises cracking hydrocarbon oil under conversion conditions of temperature and pressure to reduce a substantial proportion of the oil to hydrocarbons within the gasoline boiling range, fractionating the conversion products to separate a light normally liquid cracked naphtha fraction and a higher boiling cracked naphtha fraction, the said light naphtha fraction having an end boiling point not in excess of about 200° F. and containing a substantial proportion of olefins but being substantially free from aromatics, subjecting the said light naphtha fraction to contact in liquid phase with a volume in substantial excess of the volume of naphtha being treated of a low-boiling isoparaffin selected from the group consisting of isobutane and isopentane in the presence of a volume ratio of active alkylation catalyst to naphtha of at least about 0.5:1 in a reaction zone maintained under alkylation conditions, whereby isoparaffin is alkylated by the olefins of said light cracked naphtha fraction, and recovering from the alkylation reaction products a substantially saturated gasoline fraction of broader boiling range than that of the said light cracked naphtha fraction prior to the alkylation step.
2. The method according to claim 1, wherein the said light cracked naphtha fraction is a C₅-C₆ cut.
3. The method according to claim 1, wherein the low-boiling isoparaffin is isobutane.
4. The method according to claim 1, wherein the alkylation catalyst is strong H₂SO₄ of alkylation strength.
5. The method according to claim 1, wherein

at least a portion of the said substantially saturated gasoline produced in the alkylation of the light cracked naphtha fraction is blended with at least a portion of the said higher boiling cracked naphtha fraction.

6. The method according to claim 1, wherein the cracking of the hydrocarbon oil is carried out in the presence of an active cracking catalyst under catalytic cracking conditions.

7. The method in the manufacture of an improved motor fuel which comprises fractionating a cracked naphtha charge to separate a light normally liquid cracked naphtha fraction and a heavier cracked naphtha fraction, the said light cracked naphtha fraction being substantially free of aromatic constituents and containing a substantial amount of olefinic constituents and being of too narrow boiling range to constitute a balanced motor fuel, reacting the said light cracked naphtha fraction with added isobutane in such proportion that the molar ratio of isobutane to olefinic constituents is not less than 1:1 in contact with an active alkylation catalyst under alkylating conditions, whereby isobutane is alkylated by said olefinic constituents, and recovering from the alkylation reaction products a substantially saturated gasoline hydrocarbon fraction of broader boiling range suitable for motor fuel.

8. The method according to claim 7, wherein at least a portion of the said substantially saturated gasoline hydrocarbon fraction of broader boiling range is blended with at least a portion of the said heavier cracked naphtha fraction to produce the improved motor fuel.

9. The method according to claim 7, wherein the cracked naphtha charge is a catalytically cracked naphtha.

10. A method of producing gasoline having a low acid heat, high octane number lead response by conversion of higher boiling hydrocarbons which comprises passing the oil to be converted through a cracking zone containing an active cracking catalyst and maintained at cracking temperature, keeping said oil in contact with said cracking catalyst within said cracking zone for a period sufficient to convert a substantial portion of said oil into motor fuel constituents, thereafter separating from the cracked products a light naphtha fraction substantially free of aromatic constituents and containing a substantial amount of olefinic constituents having a high acid heat, passing the fraction so segregated in a mixture with isoparaffins in such proportion

that the molar ratio of isoparaffins to olefinic constituents is not less than one to one in contact with an active alkylating catalyst capable of accelerating the union between isoparaffins

5 and olefins to form a saturated product and maintaining said mixture in contact with said catalyst for a period sufficient to alkylate a substantial amount of said olefins in said light naphtha fraction and to increase the boiling range
10 thereof.

11. A process for the conversion of hydrocar-.

11. A process for the conversion of hydrocarbon oils to form gasoline having a low acid heat, high octane number and lead response which comprises passing the oil to be converted through

15 a cracking zone maintained at active cracking temperature, contacting said oil within said cracking zone while at active cracking temperature with a cracking catalyst, keeping said oil in contact with said catalyst for a period suffi-

20 cient to convert a substantial portion thereof into gasoline constituents, thereafter separating a light naphtha fraction substantially free of aromatic constituents and containing a relatively high concentration of olefins and a heavy naph-

25 the fraction from the cracked products, passing the light naphtha fraction so segregated through an alkylating zone containing an active alkylating catalyst, introducing isoparaffins into said alkylating zone in an amount at least equal to

30 alkylating zone in an amount at least equal to the amount of olefins contained in said light naphtha fraction to thereby maintain a molar ratio of isoparaffins to olefins of at least one to one, maintaining said alkylating zone under conditions such as to cause said isoparaffins to unite

35 ditions such as to cause said isoparaffins to unite with said olefins to form a saturated alkylate product, and thereafter combining alkylate formed from said last-named alkylating treatment with heavy naphtha from said catalytic cracking treatment to form a gasoline blend con-

40 cracking treatment to form a gasoline blend containing light naphtha alkylate and heavy cata-
lytically cracked naphtha.
